DR. D 514

Design No. 514.

Fig. 2 thru - Design from antique book
Received Oct 26, 1913.

Dec. 514

Pelatiah M. Hutton of Troy, N.Y.
Letters Patent No. 514, dated Oct. 26th 1852

The schedule referred to in these Letters Patent and making part of the same

To all whom it may concern:

Be it known that I, Pelatiah M. Hutton, of the city of Troy, in the County of Rensselaer & State of New York, have invented or produced a new and original design ornament or inflection to be cast upon cast iron cradles, and I do declare that the following is a full and exact description of the same.

In the annexed drawing Fig 1, is a descriptive view (on a larger scale than the sectional drawings) A.A. is the body or swinging part of the cradle and is only shown in this view. Fig 2. is a transverse section of one of the ends or supports (reference being had to one only in the drawings as they are both from the same pattern) and fig 3 is a longitudinal section of the same shown at B B fig 1. fig 4, is a horizontal section of the connection between the ends below the body of the cradle and Fig 5 is a vertical section of the same shown at C, fig 1. This connection is attached to the ends or supports by means of bolts and screws at D D D D fig 1. The body is attached at the tops of the support with a bolt and screw at each end at E E, fig 1. The body A.A, fig 1, and the sectional part represented by Figs 2 & 4 are the only ornamental parts of the cradle and they are ornamented with straight and curved lines as seen in the drawing.

What I claim as my invention and desire to secure by Letters Patent is the design and configuration of the ornaments upon the body A.A, fig 1, and upon the sectional parts represented by fig 2 & 4, combined as in the drawing hereto annexed to form an ornamental iron cradle.

Troy April 15th 1852.
